UNITED STATES PATENT OFFICE.

EDWARD SEAVER, JR., OF BOSTON, MASSACHUSETTS, ASSIGNEE TO THE WESTINGHOUSE MACHINE COMPANY, A CORPORATION OF PENNSYLVANIA.

FLUID-TRANSLATING DEVICE.

1,148,992.

Specification of Letters Patent. Patented Aug. 3, 1915.

Application filed August 7, 1913. Serial No. 783,551.

To all whom it may concern:

Be it known that I, EDWARD SEAVER, Jr., a citizen of the United States, and a resident of Boston, in the county of Suffolk and State of Massachusetts, have made a new and useful Invention in Fluid-Translating Devices, of which the following is a specification.

This invention relates to fluid translating devices and particularly to devices employing a stream of liquid for mechanically entraining and removing air and other non-condensable gases.

An object of my invention is to produce a fluid translating device employing a jet of liquid which is capable of condensing condensable fluids and of entraining non-condensable fluids.

A further object is to produce a high speed pump or fluid translating device capable of operating in conjunction with a condenser and of efficiently maintaining a high vacuum in the condenser.

A further object is to produce a fluid translating device or pump in which a jet of liquid, for example water, is employed in entraining and ejecting air and other non-condensable gases and which may be employed for producing and maintaining a high vacuum or for delivering air or other non-condensable gases from a low to a higher pressure.

These and other objects I attain in a condenser embodying the features herein described, and illustrated in the drawings accompanying this application and forming a part thereof.

In the drawings: Figure 1 is a longitudinal sectional view of a device embodying my invention; Fig. 2 is a sectional view on the line 2—2 of Fig. 1; and Fig. 3 is a developed section of a portion of an annular row of blades which form a detail of my invention.

Referring now to the drawings by numberals of reference, 10 designates a casing provided with a water inlet 11, an air inlet 12, and a water and air discharge port 13.

14 is a shaft extending through the end walls of the casing 10 and it is mounted in bearings 15 and 16. Within the casing 10 and fixed to the shaft 14 is a pump impeller 17 adapted to force water from the inlet 11 through the annular port 18 and then through an outlet 19 in line with the collector cone 20 in the discharge 13 of the

pump. 21 is a distributor shown as a wheel, carried by the shaft 14, said wheel having an annular row of blades 22 at right angles to the web thereof and in line with the outlet 19 and the collector cone 20. These 80 blades 22 are illustrated as being integral with the wheel but it is obvious that they may be secured thereto in any well known manner.

It is well known that a stream comprising a succession of thin leaves or films of water is more effective in entraining and ejecting non-condensable gases than a solid stream or a stream composed of a mass of separate drops. I therefore so construct the 85 blades 22 of the wheel 20 that they will segregate the stream of water delivered through the port 19 into a stream of successive leaves or films of water which is projected radially of the wheel by the velocity attained due to the pressure head imparted to it by the impeller 17. These 70 segregated films or leaves pass from the blades 22 to the collector cone 20 entraining between them films of air from the air space 75 23, the air and water being discharged to atmosphere.

In practising my invention I may segregate the leaves without imparting additional energy thereto, although in some cases it 85 may be desirable to impart additional radial velocity to them by means of the blades 22.

In Fig. 3 I have illustrated the wheel blades so constructed that the water will be 90 delivered through port 19 and blades 22 at a velocity which corresponds to the difference in absolute pressure between the pressure at the entrance to the collector cone 20 and that at the port 18. For example, 95 by means of the line 24 I have indicated the velocity of the water while the line 25 indicates the velocity of the wheel. The resultant of these two velocities is indicated by the line 26. It will therefore be apparent 100 that the blades on the wheel may be so designed that the water will be received by the wheel without impact and will simply slide through the spaces between the blades and continue in the direction of its original 105 travel, by virtue of its original velocity after being divided into thin leaves. In fact the blades 22 are preferably so arranged on the wheel that they simply act as a slicer 110 for the stream of water or liquid delivered

- through the discharge passage 19, and the blades may be so designed that the separate sheets or pistons of liquid, cut off by the inner edges of the blades, will pass through 5 the spaces between the blades without touching the blades. It will also be apparent that instead of the blades shown, a construction of wheel may be employed to impart velocity to the stream as it leaves the port 19.
- 10 It will be observed that the water passes through the air entraining wheel and the impeller 17 in series and that the wheel and impeller are on the same shaft and within the same case so that a compact device is 15 provided.

When the device illustrated is used in connection with a condenser, the port 12 will communicate with the air delivery port of the condenser, a suitable water connection 20 being also provided for the inlet port 11. It will be understood that the water leaving the blades 22 is received by the collecting cone 20, where the initial compression of the non-condensable vapor begins, it then enters 25 the diffuser 27 where its velocity energy is gradually transformed into pressure, and it is finally discharged from the diffuser at atmospheric pressure.

Having thus described my invention, what 30 I claim is:

1. An apparatus of the character described, comprising a casing having a liquid inlet port, a fluid inlet port, and a combined fluid and liquid discharge port, a pump 35 within the casing for imparting a high velocity to the liquid entering through the liquid inlet port, the outlet of said pump communicating with the fluid inlet port, rotatable means for breaking up the stream 40 of liquid delivered by the pump into a succession of relatively thin leaves, and means for receiving the stream of leaves so formed and for converting the velocity energy of the liquid into pressure energy and for dis- 45 charging the liquid from the casing.
2. An apparatus of the character de- scribed, comprising a casing having a liquid

inlet port, a fluid inlet port, and a single fluid and liquid discharge port, a pump receiving liquid from the liquid inlet port, 50 and having a discharge port located within the casing and in communication with the fluid inlet port, a bladed wheel located within the casing between the discharge port thereof and the discharge port of the pump 55 for breaking up the stream of liquid discharged from the pump into a stream of relatively thin leaves, and a combining tube and a diffuser communicating with the discharge port of the casing for receiving the 60 stream of relatively thin leaves issuing from said bladed wheel.

3. In a fluid translating device, a casing having an inlet and an outlet, a pump within the casing, and a wheel for breaking up 65 the water from the pump into thin leaves or films without imparting additional velocity thereto.

4. In a fluid translating device, a casing having an inlet and an outlet, means in the 70 casing for imparting pressure to water entering the casing, and means in series with the first named means for segregating the water into films or layers.

5. In a fluid translating device, a casing 75 having an inlet and an outlet, means in the casing for imparting a high velocity to the water entering the inlet, and means adjacent the outlet for segregating the water into films or layers. 80

6. In a fluid translating device, a casing having an inlet and an outlet, means for imparting velocity to water within the casing, and a wheel adjacent the outlet for segregating the water into films or layers with- 85 out imparting additional velocity thereto.

In testimony whereof, I have hereunto subscribed my name this twenty-sixth day of July, 1913.

EDWARD SEAVER, JR.
